WILLIAM WALLACE, OF EDINBURGH, SCOTLAND.

TELEMOTOR APPARATUS.

1,342,238.

Specification of Letters Patent.

Patented June 1, 1920.

Application filed April 4, 1918. Serial No. 226,795.

To all whom it may concern:

Be it known that I, WILLIAM WALLACE, a subject of the King of Great Britain and Ireland, and a resident of Edinburgh, Scotland, have invented a certain new and useful Improved Telemotor Apparatus, of which the following is the specification.

The invention has for its object to provide simple and effective telemotor apparatus for controlling from a central station the movements of a search-light or the like.

Application of telemotor apparatus to this purpose differs from that more usual application to the control of ships' steering gear in that in the case of ships' steering gear the apparatus is in continuous use for long periods, and therefore elaborate devices for insuring so far as possible that the transmitting apparatus and the receiving apparatus remain in consonance one with the other, are necessary, whereas, in the application to apparatus such as a search light which is used intermittently and for comparatively short periods at a time, such elaborate devices are unnecessary if their place be taken by the much simpler arrangements and system which form the subject of the present invention.

The invention relates to that kind of telemotor apparatus in which all automatic valves, automatic by-pass devices, and receiver-returning devices are discarded, and which comprises two telemotors, a transmitter and a receiver, connected in a circuit which during the period of their operation is entirely closed.

According to the invention there is provided a pump and a receiving vessel for charging the system with pressure liquid before it is put in use by way of a series of by-pass pipes which are controlled by manually operated valves all as in certain known apparatus, and there is further provided means for circulating the operating liquid through the system so that it may be rid of air, and to the same end there are provided a series of manually controlled air-release connections.

Preferably, and in order that stuffing-boxes and the like apt to leak may be avoided as far as possible, the telemotors are of the type in which a double-ended ram operates in a cylinder with closed ends, the ram having on it a rack engaged by a pinion on a spindle passing out through an aperture in the cylinder casing and connected to an

operating handle or to the gearing moving the search light as the case may be.

In carrying out the invention two sets of this apparatus are applied—one to train 60 and the other to control the elevation of the search light. The transmitters are provided with pointers moving over scales divided in degrees of elevation and training, and similar scales are provided on the search light 65 which latter is operated by any convenient form of gearing from the receivers.

Preferably, there is provided at the transmitting station a sighting device of telescope or other type operatively connected to 70 the transmitter in suchwise that the operator of the transmitter can lay the search light he operates upon any desired target.

The general lay out of an example of the carrying out of the invention is shown in 75 diagram form in Figure 1 Sheet 1 of two appended sheets of drawings, while in Sheet 2 are shown in detail examples of the construction of the several parts, Fig. 2 being a sectional elevation of a transmitter for 80 training purposes, Fig. 3 a like view of the upper part of a transmitter controlling elevation, and Fig. 4 a like view of a receiver for either purpose. Fig. 5 is a broken plan of the operating gear for the search light 85 training receiver, and Fig. 6 is a broken elevation thereof.

The transmitting and receiving instruments while generically of types known in prior telemotors, differ in those details 90 which adapt them for their specific purpose. As shown in Figs. 2 and 3, the transmitters each consist of a vertical cylinder A in which operate two pistons A¹, A² mounted on the ends of a screwed piston rod A³ kept 95 from turning within the cylinder by a feather A⁴ engaging a groove in it. A nut A⁵ held in a recess formed between the halves of the cylinder A engages the rod A³. This nut A⁵ has cut about its periphery spur 100 teeth with which there engages a pinion A⁶ on a vertical shaft A⁷ supported in brackets from the cylinder structure.

In the case of the training transmitter shown in Fig. 2, this shaft carries at its upper end a handwheel A⁸ by which the transmitter is operated. On the shaft A⁷ immediately beneath the handwheel is a worm A⁹ gearing with a wormwheel on a shaft A¹⁰ which is connected by bevel gearing A¹¹ 110 with a vertical shaft A¹² on the upper end of which is mounted on horizontal pivots a

sighting telescope A¹³. It is clear that operation of the handwheel A⁸ causes conjoint and relative movements of the telescope A¹³ and of the transmitter pistons A¹, A².

5 In the case of the elevating transmitter shown in Fig. 3, the vertical shaft A⁷ carries at its upper end a bevel wheel A¹⁴ gearing with a bevel wheel A¹⁵ on a horizontal shaft A¹⁶ on the ends of which are handwheels A¹⁷. The shaft A¹⁶ is screwed, and there engages it a nut A¹⁸ formed with a pointer indicating upon a scale A¹⁹. Air release plugs A²⁰ are provided at the upper end of each cylinder for the release of occluded air.

10 The receivers, of which one is shown in Fig. 4, are of the type in which the cylinder B has within it a piston B¹ on which is formed a rack B² and which is provided at 20 its ends with cup-leathers B³, B⁴. A pinion B⁵ engaged by the rack B² is mounted in a cavity midway in the cylinder and is carried on a shaft B⁶ passing out through a stuffing-box. The shaft B⁶ is of course operatively 25 connected to either the training or the elevating gear of the search light as the case may be.

15 The other receiver BB is illustrated in Figs. 5 and 6. As in the one just described, 30 the cylinder B contains a piston B', on which is formed a rack B² with cup-leathers B³ and B⁴. A pinion B⁵ engaged by the rack is mounted on the shaft B⁶ which also carries a gear B⁷ of greater diameter. The 35 latter meshes with the quadrant B⁸ on the shaft B⁹ which passes up through the base B¹⁰ supporting the search light (not shown) secured to and turning with the shaft B⁹.

20 In the diagram Fig. 1 there is shown the 40 lay out of a complete installation for training and elevating a search light, there being a training transmitter A, an elevating transmitter AA, a training receiver B, and an elevating receiver BB. Main line pipes C 45 connect the opposite ends of the transmitter A with the opposite ends of the receiver B, and similarly the transmitter AA with the receiver BB. In this circuit are valve box devices D (throughout the diagram all 50 valves are shown open) by which, firstly, by-pass connection may be made between the two line pipes C, secondly, between these pipes and a pressure chamber E by way of pipes F, and thirdly between them and 55 a storage tank G by way of pipes H. Valve controlled connection is also provided between the opposite ends of each receiver (B, BB) by way of pipes J, while the pressure chamber E and the storage tank G are connected by a valve controlled pipe K. Air release valves L are provided on the transmitters and receivers. A pressure gage M, is provided on the pressure chamber E, and a pump of any convenient form is provided 60 which draws from the storage tank G and

delivers to the pressure chamber E. As here shown diagrammatically at G' this pump is arranged within the storage tank G.

65 In order to put the apparatus into operating condition, one system—say the elevating system—is cut off from the pressure chamber E and the storage tank G. Connection is then made by operation of the valves between the other system and the pressure chamber and storage tank, the pistons of 70 the transmitter A are placed in mid position, the by-pass connection between its opposite ends is closed and all the air-release valves L are opened as is also the by-pass between opposite ends of the receiver B. 75 By means of the pump connected to the pressure chamber E, liquid is circulated through the system from and back to the storage tank G until the liquid flows from the air escape valves L which are then 80 closed. Pumping is then continued until all entrained air is removed from the system which can be ascertained by operation of the transmitter which should then be 85 free from elastic yield. The connections between the storage tank and pressure vessel and the system are then closed. The same 90 operation is then performed on the elevating system.

95 The latter system having been freed from air, both systems are jointly connected by operation of their several valves to the pressure vessel E, and the pump, drawing from the storage tank G, is then operated until a substantial pressure (say 100 lbs. per sq. 100 in.) subsists in the pressure vessel and so in the two systems. The transmitter by-pass valves are then closed and the apparatus is ready for use.

105 It is to be understood that the pipe C which establishes communication between the top of the cylinder A and the left-hand end of cylinder B is not obstructed by the closing of the by-pass valve D of cylinder A. When the valve is in this position, circulation takes place as follows:—From the pipe F to the bottom of cylinder A, thence by pipe C to the right hand end of cylinder B, thence by bypass J, through the valve D (which is open), and into the left hand end 110 of cylinder B, from which the liquid has free passage by pipe C to the top of cylinder A.

115 It is to be noted that only one system is freed from air at a time. When the training system has been so freed the connection between this system and the storage tank and pressure vessel are closed. The corresponding connections for the elevating system are then opened and air similarly 120 expelled. Both systems are then conjointly connected to the pressure vessel and storage tank, and the pump is operated until the desired pressure exists in both systems. Whenever the installation is to be used, the 130

valves D of the receiver E are closed; there being no provision for leakage losses while the search light is actually in use.

What I claim is:—

- 5 1. In a telemotor system, a transmitter, a receiver, a direct, constant and entirely closed circuit operatively connecting the same, in combination with a storage tank, a pump for forcing operating liquid through 10 the system from said storage tank to eliminate air (other than that in solution), together with a pressure vessel connected in the system and with the pump for maintaining in the system a pressure greater 15 than that of the atmosphere, and means for cutting the pump and storage tank out of the system during the operation of the telemotor.
2. In a telemotor system, a transmitter, a receiver, a direct, constant and entirely closed circuit operatively connecting the same, in combination with a storage tank, a pump for forcing operating liquid through 20 the system from said storage tank to eliminate air (other than that in solution), together with a pressure vessel connected in the system and with the pump for maintaining 25

in the system a pressure greater than that of the atmosphere, and means for cutting the pump, storage tank and pressure chamber 30 out of the system during the operation of the telemotor.

3. In a telemotor system, a transmitter, a manually controlled device for operating the transmitter, a sighting device, and an 35 operative connection between the manual operating means and the sighting device for operating the transmitter and sighting device in harmony with each other.

4. In a telemotor system, a transmitter, a 40 sighting device operatively associated therewith, a receiver, an apparatus actuated thereby, together with means for actuating said transmitter to operate the latter, the sighting device, the receiver and the apparatus 45 moved thereby all in harmony.

In testimony whereof I have signed my name to this specification, in the presence of two subscribing witnesses.

WILLIAM WALLACE.
